UNITED STATES PATENT OFFICE.

ANNA K. MAY, OF PHILADELPHIA, PENNSYLVANIA, ASSIGNOR TO WILLIAM H. McCALLUM AND IRVING McCALLUM, OF SAME PLACE.

DESIGN FOR CARPET.

SPECIFICATION forming part of Design No. 28,830, dated June 7, 1898.

Application filed May 3, 1898. Serial No. 679,645. Term of patent 34 years.

To all whom it may concern:

Be it known that I, ANNA K. MAY, a citizen of the United States, residing at the city of Philadelphia, in the county of Philadelphia and State of Pennsylvania, have invented and produced a new and original Design for a Carpet or other Fabric, of which the following is a specification, reference being had more particularly to the accompanying drawing, illustrating the same and forming part thereof.

The leading feature of my design is an Arabic pattern of damask and set figures, with small figures connected by leaf forms to present a kind of panel.

In the drawing, a is the body, b the border, and a b the complete carpet. c are damask and set figures, and d is a panel made up of leaf forms and small figures, substantially as shown.

What I claim as my invention, and desire to secure by Letters Patent, is—

1. In a design for a carpet, the body a, substantially as shown.

2. In a design for a carpet, the border b, substantially as shown.

3. The design for a carpet consisting of the body a, and border b, substantially as shown.

In testimony whereof I have hereunto signed my name.

ANNA K. MAY.

In presence of—

HARRY O. SWEARER,
CHAS. J. SCHAEFER.
